UNITED STATES PATENT OFFICE

98,286

DESIGN FOR A REFLECTOR OR SIMILAR LIGHTING FIXTURE

Wesley Wilson, Chicago, Ill.

Application August 30, 1934, Serial No. 53,119

Term of patent 7 years

To all whom it may concern:

Be it known that I, Wesley Wilson, a citizen of the United States, residing at Chicago, in the county of Cook and State of Illinois, have invented a new, original, and ornamental Design for a Reflector or Similar Lighting Fixture, of which the following is a specification, reference being had to the accompanying drawing, forming a part thereof.

In the drawing,—

Figure 1 is a perspective view of a reflector or similar lighting fixture embodying my design;

Fig. 2 is a front view; and

Fig. 3 is an end elevation.

The construction, as shown, comprises a generally cylindrically shaped body portion, having an inner reflecting surface, and generally circular end portions which are of transparent or translucent material, as shown in Fig. 2. The edges of the body portion are shown as bulged slightly, so that the hood portion extends at its center beyond the edges of the end portions.

I claim:

The ornamental design for a reflector or similar lighting fixture, substantially as shown and described.

WESLEY WILSON.
